DESIGN FOR A WATER SPRAY GUN

William M. Cissell, St. Mathews,
near Louisville, Ky.

Application February 11, 1946, Serial No. 126,438

Term of patent 14 years

(Cl. D62—2)

To all whom it may concern:

Be it known that I, William M. Cissell, a citizen of the United States, residing at St. Mathews, near Louisville, in the county of Jefferson and State of Kentucky, have invented a new, original, and ornamental Design for a Water Spray Gun, of which the following is a specification, reference being had to the accompanying drawing, forming part thereof.

Figure 1 is a perspective view of a water spray gun, showing my new design;

Figure 2 is an elevational view of one end thereof; and

Figure 3 is an elevational view of the other end thereof.

I claim:

The ornamental design for a water spray gun, substantially as shown.

WILLIAM M. CISSELL.
